GARMENT BAG

Irving L. Braverman, Brooklyn, N. Y.

Application July 24, 1951, Serial No. 238,318

10 Claims. (Cl. 190—43)

1

This invention relates to improvements in garment bags.

One object of the present invention is the provision of a garment bag having an improved frame construction for supporting the garment bag and the contents thereof.

Another object of the present invention is the provision of an improved spreader frame for a garment bag that is of simplified and durable construction, light in weight and economical to manufacture.

Another object of the present invention is the provision of a garment bag having an improved frame construction in which the frame is provided with means for attachment to both a carrying handle and a supporting hanger for supporting the garment bag and the contents thereof.

Another object of the present invention is the provision of an improved garment bag and frame therefor in which the frame may be assembled to the bag with extreme ease by a relatively unskilled person, and in which the frame construction is inherently self-compensating for variations in the positioning of the complementary portions of the bag to provide for such ease of assembly of the frame to the bag.

Yet another object of the present invention is the provision of an improved garment bag in which the slide fastener is secured to a portion of the bag in an improved manner whereby to provide a guide and re-enforced support for the operating tab and to provide for the ease of operation thereof.

The above and other objects, features and advantages of the present invention will be more fully understood from the following description considered in connection with the accompanying drawings.

In the drawings:

Fig. 1 is a perspective view of the garment bag according to the present invention in its unfolded condition;

Fig. 2 is a perspective view of the garment bag in its folded condition;

Fig. 3 is a fragmentary sectional view taken on the line 3—3 of Fig. 1;

Fig. 4 is a fragmentary sectional view taken on the line 4—4 of Fig. 3;

Fig. 5 is a fragmentary sectional view taken on the line 5—5 of Fig. 3;

Fig. 6 is a fragmentary sectional view taken on the line 6—6 of Fig. 1; and

Fig. 7 is a fragmentary sectional view taken on the line 7—7 of Fig. 2.

Referring to the drawings and more particu-

larly to Figs. 1 through 4 thereof, the garment bag 10 according to the present invention comprises a casing or envelope 12 and a frame structure 14. The casing or envelope 12 is formed of any suitable flexible material and is provided with a top wall 16, a bottom wall 18, a front wall 20, a back wall 22 and side walls 24 and 26. Corner reinforcing bindings 28 of plastic or any other suitable material are stitched to the edges or corner portions of the bag 10 and re-enforcement strips 30 are provided on the top wall 16 to reinforce the portions of the bag 10 that are normally subject to the greatest amount of wear. The front wall 20 is provided with a closure flap portion 32 which is adapted to be unfastened from the wall 20 to gain access to compartment 51 in the interior of the bag 10. For this purpose the portion 32 is provided with a slide fastener 34 having an operating tab 36. It will be understood that the slide fastener 34 has a longitudinal strip portion 38 thereof suitably secured to a peripheral portion 32 of the bag 10 and a complementary strip portion 44 suitably secured to the adjacent peripheral portions of the front wall 20, the operating tab 36 being effective for fastening and unfastening the flap portion 32 to the front wall 20. The strip portion 38 of the slide fastener 34 that is secured to the flap 32 is secured thereto in a conventional manner, that is the strip portion 38 is superposed on the periphery of flap 32 of the garment bag 10 and stitched thereto by lines of stitching 40 as shown in Fig. 3. The strip portion 42 however is folded over upon itself upon a longitudinal median line and the portion 44 adjacent to the wall 20 is stitched thereto by a line of stitching 46 as shown in Fig. 3. A binding strip 48 of plastic or any other suitable material is suitably secured in doubled over fashion as by the line of stitching 46 to the above described securing of the strip portion 42 and its associated portions of wall 20. It will thus be seen that the binding strip 48, and the adjacent end portions of the wall 20 and the adjacent portion of the strip portion 42 lying within the binding 48, provide a guide and re-enforced support for the operating tab 36 and facilitates the ease of operation thereof. It will be understood that the slide fastener 34 is conventional in all respects except that the longitudinal strip portion 42 of said slide fastener is secured to the adjacent portions of the wall 20 in a doubled over fashion, as best shown in Fig. 3, and as described above. The garment bag 10 is also provided with a separate compartment 50 at the lower part, to which access is gained from the outside of the

garment bag. The compartment 50 is defined by the wall 52, which is secured at one end to the bottom front corner 54 of the garment bag and at the other end to an intermediate portion of the front wall 20, and the lower part of the front wall 20. The wall 52 has its sides suitably secured to the front side corners of the bag 10 as by means of the same line of stitching that secures bindings 28 to the corners of the bag. To gain access to the compartment 50 there is provided a slide fastener 56 transversely secured to an intermediate portion of the front wall 20, as shown in Fig. 6. It will be seen that the compartment 50 in no way interferes with the contents of the compartment 51, it being understood that said compartments are distinct and separate. It will also be noted that the compartment 51 extends uninterruptedly for the full length of the bag for the reception of garments in their extended condition.

The frame structure 14 formed of metal or other suitable material comprises a spreader frame member 59 of rectangular outline having integral spaced sides 58 and ends 60. The spreader frame 59 fits the garment bag 10 near the top thereof and has a rectangular outer periphery corresponding to the cross-sectional shape of the envelope or casing 12. Although the spreader frame is shown as being of substantially rectangular contour it will be understood that such frame may be of other suitable contours. The spaced sides 58 of the frame 59 are provided with downwardly looped portions 62 centrally positioned intermediate the ends thereof, said looped portions being adapted for a purpose to be described in detail hereinafter. The frame structure 14 also comprises a transverse second frame member 64 having an integral upper horizontal member 66, an integral lower horizontal member 68 and connecting portions 70, as shown in Fig. 3. The upper horizontal member 66 is provided with an upwardly extending centrally positioned looped portion 72, said looped portion being for a purpose to be described in detail hereinafter. The frame member 64, and more particularly the lower horizontal member 68 thereof, is adapted to provide a bar support for a plurality of garment hangers 11 in laterally spaced disposition. The frame member 64 is secured to the spreader frame 59, the end portions of the upper horizontal member 66 being adapted to be received in the downwardly extending looped portion 62 of the spreader frame 59. The frame member 64 is provided with an additional shaft 74 parallel to the support shaft or member 68 and spaced therefrom. The additional shaft 74 is secured to the connecting portions 70 in any suitable manner, as by welding. It will be understood that the additional shaft 74 is effective to prevent the disengagement from the support shaft 68 of garment hanger hooks supported thereon.

The garment bag 10 is provided with a pair of elongated spaced openings 76 extending through the top wall 16 of the bag and a circular aperture 78 centrally positioned between the openings 76. The openings 76 and the aperture 78 are provided with suitable grommets 77 and 79, respectively, secured to the top wall 16 of the garment bag 10. The garment bag is provided with a carrying handle 80 fabricated from any suitable material and having looped end portions 82, said carrying handle being adapted to be connected to the frame structure 14. The carrying handle 80 which is disposed externally of the bag

and at the top thereof is provided with a triangular shaped link element 84 at each end of the handle. For securing the frame 59 and concomitantly the transverse frame member 64 to the link elements 84 there are provided hook elements 86 which pass through the pair of spaced openings 76 which extend through the top wall 16, and are adapted to secure the ends of the carrying handle 80 to the spreader frame 59. To this end hook elements 86, which are generally U-shaped, have their bight portions embracing the vertex portions 88 of the link elements 84 and each of the end portions of the elements 86 are bent over spaced portions 90 of the spreader frame 59 immediately adjacent the downwardly extending looped portions 62, as shown in Figs. 3, 4 and 5. At the same time the upwardly extending looped portion 72 of the frame member 64 will extend through the aperture 78 in the top wall 16, said looped portion having secured thereto a supporting hanger 92 having a hooked portion 94. It will be understood that the lower end of the supporting hanger 92 has a portion thereof bent over the looped portion 72, said connection providing for substantially universal movement of the hanger 92 relative to the looped portion 72.

It will be observed that the spreader frame 59 and the transverse frame member 64 are each of integral and endless construction and are secured to each other without the use of extraneous fastening means. It will be noted that the spaced sides 58 of the spreader frame 59 and its attached connections to the ends of the handle 80, namely the hook members 86 and the link elements 84 have a range of relative transverse movement with respect to the top wall 16 of the bag and the upper horizontal member 66 of the frame member 64. It will be understood that the spaced sides 58 of the frame 59 have a range of movement towards each other due to the upper horizontal member 66 being relatively loosely secured in the downwardly extending looped portions 62 of the spreader frame 59. The above referred to relative movement of the spaced sides 58 of the frame 59 and its associated connecting means to the ends of the handle 80 provides a frame construction which is inherently self-compensating for variations in the positioning of the complementary portions of the bag, namely the pair of spaced openings 76, to provide for extreme ease of assembly of the frame 14 to the garment bag 10. It will thus be seen that the exact spacing of the openings 76 is in no wise critical due to the aforescribed self-compensating feature of the frame structure whereby the frame may be assembled to the bag with ease by a relatively unskilled person. A reinforcing strip 15 of any suitable material is secured in any conventional manner to the underside of the top wall 16, as by means of the grommets 77 and 79, said strip being effective to reinforce the area of the underside of the top wall adjacent to the attachment provisions aforescribed.

The garment bag 10 is adapted to be folded along a median transverse line and secured in such folded condition for ease of carrying, as will be readily understood. For this purpose there is provided a pair of male fastener elements 96 secured to the upper part of the front wall 20 and a pair of complementary female fastener elements 98 suitably affixed to the lower end of the back wall 22 of the bag. It will thus be seen by folding the bag 10 along a median transverse line and snapping the fastener elements 98 over the

complementary fastener elements 96 the garment bag will be neatly secured in its folded condition as clearly shown in Fig. 2.

It will be appreciated that the garment bag 10 embodying the frame structure 14 provides both a carrying handle 80 and a supporting hanger 92 for supporting the garment bag 10 and the contents thereof. Thus the garment bag may be supported by the hanger 92, or alternatively by the carrying handle 80, it being appreciated that the hanger 92 is the normal support for the bag and its contents in a clothes closet or in an automobile, and that the carrying handle 80 is the normal support for carrying the bag by hand. It is to be understood that the carrying handle 80, hanger 92, and the associated frame structure support both the casing 12 and the contents of the bag, the casing itself having no substantial stress put upon it.

It will thus be seen that the above described garment bag 10 is provided with an improved frame construction 14 for supporting the garment bag and the contents thereof. The improved spreader frame 14 is of simplified and durable construction, light in weight consistent with strength, and economical to manufacture. The improved frame construction 14 in association with the garment bag 10 is provided with means for attachment to both the carrying handle 80 and a supporting hanger 92, both the carrying handle and supporting hanger being each adapted for supporting the garment bag and the contents thereof. As has been pointed out in detail above, the improved garment bag and associated frame structure may be assembled with extreme ease by a relatively unskilled person, this ease of assembly being obtained by the inherently self-compensating frame construction for variations in the positioning of the complementary portions of the bag. It will be noted that the lower horizontal member 68, of the transverse frame 64, extends for the full length of the frame 64 whereby the lower horizontal member 68 is adapted to support a maximum number of garment hangers 11 in laterally spaced disposition.

While there is shown and described herein certain specific structure embodying the invention, it will be manifest to those skilled in the art that various modifications and rearrangements of the parts may be made without departing from the spirit and scope of the underlying inventive concept and that the same is not limited to the particular form herein shown and described except insofar as indicated by the scope of the appended claims.

Having thus described my invention, what I claim and desire to secure by Letters Patent, is:

1. A garment bag comprising a flexible envelope having a supporting hanger, a handle and a plurality of apertures at the top thereof, and an inner spreader frame positioned in the top portion of said envelope and adapted to support said envelope and the contents thereof, said frame comprising a skeleton frame member having an outer periphery corresponding to the cross-sectional shape of said envelope, and a transverse frame member adapted to support a plurality of garment hangers, said transverse frame member having an intermediate portion thereof extending through a central aperture in the top of said envelope, said intermediate portion being secured to said supporting hanger, and means extending from the extremities of said transverse frame member through spaced apertures in the top of

said envelope, said transverse frame member having a bottom shaft extending for the full length of said last mentioned frame member, said shaft being adapted to support a plurality of garment hangers in laterally spaced disposition, and said handle having means at the ends thereof for securing to said means of the transverse frame member whereby said bag and the contents thereof may be supported by either said handle or said supporting hanger.

2. A garment bag comprising a flexible envelope having a supporting hanger, a handle and a plurality of apertures at the top thereof, and an inner spreader frame positioned in the top portion of said envelope and adapted to support said envelope and the contents thereof, said frame comprising a skeleton frame member having an outer periphery corresponding to the cross-sectional shape of said envelope, and a transverse frame member adapted to support a plurality of garment hangers, said transverse frame member having a bottom shaft extending for the full length of said last mentioned frame member, said shaft being adapted to support a plurality of garment hangers, said transverse frame member having an intermediate portion thereof extending through a central aperture in the top of said envelope, said intermediate portion being secured to said supporting hanger, and means extending from the extremities of said transverse frame member through spaced apertures in the top of said envelope, said transverse frame member having a bottom shaft extending for the full length of said last mentioned frame member, said shaft being adapted to support a plurality of garment hangers in laterally spaced disposition, and said handle having means at the ends thereof for securing to said means of the transverse frame member whereby said bag and the contents thereof may be supported by either said handle or said supporting hanger.

3. A garment bag comprising a flexible envelope having a supporting hanger, a handle and a plurality of apertures at the top thereof, and an inner spreader frame positioned in the top portion of said envelope and adapted to support said envelope and the contents thereof, said frame comprising a skeleton frame member having an outer periphery corresponding to the cross-sectional shape of said envelope, and a transverse frame member adapted to support a plurality of garment hangers, said transverse frame member having an intermediate portion thereof extending through a central aperture in the top of said envelope, said intermediate portion being secured to said supporting hanger, and means extending from the extremities of said transverse frame member through spaced apertures in the top of said envelope, said transverse frame member having a bottom shaft extending for the full length of said last mentioned frame member, said shaft being adapted to support a plurality of garment hangers in laterally spaced disposition, and said handle having means at the ends thereof for securing to said means of the transverse frame member whereby said bag and the contents thereof may be supported by either said handle or said supporting hanger, said transverse frame member being of integral and endless construction.

4. A garment bag comprising a flexible envelope having a supporting hanger, a handle and a plurality of apertures at the top thereof, and

an inner spreader frame positioned in the top portion of said envelope and adapted to support said envelope and the contents thereof, said frame comprising a skeleton frame member having an outer periphery corresponding to the cross-sectional shape of said envelope, and a transverse frame member adapted to support a plurality of garment hangers, said transverse frame member having an intermediate portion thereof extending through a central aperture in the top of said envelope, said intermediate portion being secured to said supporting hanger, and means extending from the extremities of said transverse frame member through spaced apertures in the top of said envelope, said transverse frame member having a bottom shaft extending for the full length of said last mentioned frame member, said shaft being adapted to support a plurality of garment hangers in laterally spaced disposition, and said handle having means at the ends thereof for securement to said means of the transverse frame member whereby said bag and the contents thereof may be supported by either said handle or said supporting hanger, said transverse frame member being of integral and endless construction and having an additional shaft parallel to said bottom support shaft and slightly spaced therefrom, said additional shaft being effective to prevent the disengagement from said bottom support shaft of garment hanger hooks supported thereon.

5. In a garment bag having a top provided with a pair of spaced openings therethrough, a frame structure disposed within the bag at the top thereof and comprising a first frame fitting the bag near the top thereof and having spaced sides and ends adjacent the sides and ends, respectively, of the bag, a second frame extending transversely between said spaced sides of said first frame and concomitantly extending between the opposite sides of the bag, said second frame having integral upper and lower horizontal members, said lower member providing a bar support for a plurality of garment hangers, a carrying handle disposed externally of the bag at the top thereof, and a pair of connections between the ends of the handle and said first frame, said connections extending through said openings, respectively, in the top of the bag, said connections comprising hook members attached to intermediate portions of said first frame and link elements secured to said hook members and the extremities of said carrying handle, said spaced sides of said first frame having downwardly looped portions intermediate the ends thereof, said downwardly looped portions being adapted to support said second frame.

6. In a garment bag having a top provided with a pair of spaced openings therethrough, a frame structure disposed within the bag at the top thereof and comprising a first frame fitting the bag near the top thereof and having spaced sides and ends adjacent the sides and ends, respectively, of the bag, a second frame extending transversely between said spaced sides of said first frame and concomitantly extending between the opposite sides of the bag, said second frame having integral upper and lower horizontal members, said lower member providing a bar support for a plurality of garment hangers, a carrying handle disposed externally of the bag at the top thereof, and a pair of connections between the ends of the handle and said first frame, said connections extending through said openings, respectively, in the top of the bag, said second frame having an additional shaft parallel to said lower horizontal member and slightly spaced therefrom, said additional shaft being effective to prevent the disengagement from said lower horizontal member of garment hanger hooks supported thereon.

frame having an additional shaft parallel to said lower horizontal member and slightly spaced therefrom, said additional shaft being effective to prevent the disengagement from said lower horizontal member of garment hanger hooks supported thereon.

7. In a garment bag having a top provided with a pair of spaced openings therethrough and a central aperture positioned between said spaced openings, a frame structure disposed within the bag at the top thereof and comprising a first frame fitting the bag near the top thereof and having spaced sides and ends adjacent the sides and ends, respectively, of the bag, a second frame extending transversely between said spaced sides of said first frame and concomitantly extending between the opposite sides of the bag, said second frame having integral upper and lower horizontal members, said upper member having an upwardly extending looped portion extending through said central aperture, a supporting hanger secured to said looped portion, said lower member providing a bar support for a plurality of garment hangers, a carrying handle disposed externally of the bag at the top thereof, and a pair of connections between the ends of the handle and said first frame, said connections extending through said openings, respectively, in the top of the bag.

8. In a garment bag having a top provided with a pair of spaced openings therethrough and a central aperture positioned between said spaced openings, a frame structure disposed within the bag at the top thereof and comprising a first frame fitting the bag near the top thereof and having spaced sides and ends adjacent the sides and ends, respectively, of the bag, a second frame extending transversely between said spaced sides of said first frame and concomitantly extending between the opposite sides of the bag, said second frame having integral upper and lower horizontal members, said upper member having an upwardly extending looped portion extending through said central aperture, a supporting hanger secured to said looped portion, said lower member providing a bar support for a plurality of garment hangers, a carrying handle disposed externally of the bag at the top thereof, and a pair of connections between the ends of the handle and said first frame, said connections extending through said openings, respectively, in the top of the bag.

9. In a garment bag having a top provided with a pair of spaced openings therethrough and a central aperture positioned between said spaced openings, a frame structure disposed within the bag at the top thereof and comprising a first frame fitting the bag near the top thereof and having spaced sides and ends adjacent the sides and ends, respectively, of the bag, a second frame extending transversely between said spaced sides of said first frame and concomitantly extending between the opposite sides of the bag, said second frame having integral upper and lower horizontal members, said upper member having an upwardly extending looped portion extending through said central aperture, a supporting hanger secured to said looped portion, said lower member providing a bar support for a plurality of garment hangers, a carrying handle disposed externally of the bag at the top thereof, and a

pair of connections between the ends of the handle and said first frame, said connections extending through said openings, respectively, in the top of the bag, said spaced sides of said first frame having downwardly extending looped portions intermediate the ends thereof, and said second frame having its upper member supported by said downwardly looped portions whereby said bag and the contents thereof may be supported by either said handle or said supporting hanger.

10. In a garment bag having a top provided with a pair of spaced openings therethrough, a frame structure disposed within the bag at the top thereof and comprising a first frame fitting the bag near the top thereof and having spaced sides and ends adjacent the sides and ends, respectively, of the bag, a second frame extending transversely between said spaced sides of said first frame and concomitantly extending between the opposite sides of the bag, said second frame having integral upper and lower horizontal members, said lower member providing a bar support for a plurality of garment hangers, a carrying handle disposed externally of the bag at the top thereof, and a pair of connections between the 25

ends of the handle and said first frame, said connections extending through said openings, respectively, in the top of the bag, said first frame being integral and of generally rectangular outline and said second frame being integral.

IRVING L. BRAVERMAN.
